WEB-PRINTING MECHANISMS WITH INTERMITTENTLY ROTATABLE FEED MEANS

Brian William Edgeley and John Basil Cousins, London, England, assignors, by mesne assignments, to Form Master Limited, Peterborough, England

Filed Mar. 19, 1962, Ser. No. 180,512

Claims priority, application Great Britain, Mar. 24, 1961, 10,906/61

9 Claims. (Cl. 101—228)

The invention relates to web-fed printing machines of the kind having a continuously rotatable printing couple operable to print intermittently and an intermittently rotatable web feeding means for feeding the web through the couple during printing operations. One such machine is disclosed in Dyke United States Patent No. 3,052,182 of September 4, 1962, and the present invention is particularly, but not exclusively, concerned with improvements in that machine. The improvements are particularly concerned with controlling the feed of the web in timed relation with the printing operations.

The invention provides a machine of the above kind characterised by means for driving the web feeding means comprising a continuously rotatable driving member, a driven member coupled to the feeding means, an electrically operable clutch between the driving and driven members, switch means controlling engagement and disengagement of the clutch, a programme member driven in synchronism with the printing couple and operable on the switch means to effect engagement of the clutch each time feed of the web is to start and a cam or the equivalent driven in synchronism with the printing couple and operable on the switch means to effect disengagement of the clutch each time feed of the web is to stop.

Preferably the timing of the operation of the programme member is variable in relation to the rotation of the printing couple.

Although as later described other form of programme member may be used, it is preferred that the member is an endless flexible band having a notch or projection (or several such) engageable with the switch means to effect operation thereof.

The clutch may be an epicyclic gear train having driving, driven and reaction members of which the driving member is continuously rotatable with the printing couple, the driven member is coupled to the web feeding means and there is a pawl and ratchet mechanism for releasably holding the reaction member, with a solenoid for effecting engagement or disengagement of the pawl, the energisation state of the solenoid being under the control of the switch means aforesaid.

A specific embodiment of a machine according to the invention will now be described, by way of example, with reference to the accompanying drawings, in which:

FIGURE 1 is a side view showing the general layout of the machine,

FIGURE 2 is a diagrammatic and explanatory view showing the driving and control means for the web-feed rollers viewed in the same direction as in FIGURE 1, and

FIGURE 3 is a diagrammatic view showing the driving and control means for the web-feed rollers viewed in the opposite direction to that in FIGURE 1.

The machine forming the subject of this example is basically the same as that disclosed in the said United States Patent No. 3,052,812. It comprises support and driving means for a supply reel 30 of paper and for a rewind reel 52. The driving means for each reel include an electromagnetic clutch and brake controlled by danc-
ing idler rollers 31 and 92. From the supply reel 30 the web 32 is fed through a punching and perforating section

2

A, then through a printing section B and finally to the rewind reel 52.

The printing section comprises continuously rotatable lithographic printing cylinders 44, 45 which, normally print over only a part of their circumference, and a numbering unit comprising cylinders 46 and 190 which also rotate continuously. These cylinders are driven by gears from the cylinder 45.

To feed the web there are two pairs of rollers 33, 35 and 48, 49. These rollers are driven, intermittently, by the mechanism about to be described, the arrangement being such that the web is fed during the printing operation of the cylinders and is stopped during the whole, or a part, of the periods in which the cylinders rotate without printing.

The roller 33 is driven by chain 71 from a sprocket on shaft 72 which carries the roller 48 and which is driven and controlled as follows. The drive is taken from the shaft 146 of the numbering cylinder or drum 46, this shaft being continuously driven, from cylinder 45 as already mentioned. Secured to the shaft 146 (later called the numbering shaft) there is the sun-wheel 301 an epicyclic gear mechanism having planet wheels 302 on a rotatable planet carrier 304. The annulus or gear ring 300 is engaged with the planet wheels and attached to a large sprocket wheel 305 which is connected by roller chain 306 to a sprocket wheel 307 of half the diameter (giving a 2:1 ratio) fixed on the shaft 72. A ratchet wheel 308 is secured to the planet carrier 304 and a pawl 310 operated by a solenoid 311 is provided for engaging the ratchet teeth and so stopping rotation of the carrier 304. When so engaged, the numbering shaft 146 drives the shaft 72, with a total gear ratio of 6:1 through the epicyclic gear and the chain drive. The ratchet wheel and pawl accordingly provide a releasable clutch between the numbering shaft 146, which rotates continuously, and the shaft 72 which drives the web-feeding rollers 33 and 48.

The following mechanism is employed to effect engagement and release of the clutch at the times appropriate to feed the paper web by the desired amounts during printing operations. Rotatable with the numbering shaft 146 there is a small type cam 312 and rotatable with the feed shaft 72 there is a detent wheel 313 with six notches 314 in its periphery. A lever 316 extends between these two members and has fixed on one end a follower 317 for the cam and on the other end a detent wedge or finger 318 for engaging in the notches 314. The arrangement is that over a small arc of movement the cam 312 rocks the lever 316 to disengage the finger 318 from a notch 314 in the detent wheel, the finger is held from the wheel during the remainder of a revolution of the cam and is then allowed to drop onto the wheel and engage in the notch 314 next to arrive opposite the finger thereby to stop and locate the detent wheel and feed shaft 72. The feed shaft 72 is therefore freed during a major portion of each revolution of the numbering shaft 146 and is positively held and located at a precise position once during each revolution.

When the finger 318 is held out of the notches 314 in the detent wheel, the lever 316 engages and closes a micro-switch 320 in a holding circuit for an electrical relay 321. This relay has two sets of contacts, one set, 322, being in the said holding circuit so that the relay is self-holding so long as the micro-switch is closed. The other set, 323, is in an energising circuit for the solenoid 311 so that energisation of the relay will effect energisation of the solenoid and engagement of the clutch. This set of contacts also controls a magnetic brake 326 on the feed shaft 72 and is arranged so that when the solenoid is de-energised and the finger 318 is out of a notch 314, the

brake is engaged, thereby ensuring that positive control of the feed shaft is always maintained.

To effect the energisation of the relay coil 321 at the appropriate times there is an endless flexible plastic belt 328 which is driven by a pin wheel 329 having pins 330 engaging in holes 331 in the belt, the pinwheel rotating continuously with the printing cylinder 45 and being driven by gears therefrom. This belt has a notch 333, or notches, in one side edge and this edge runs against an operating roller 334 for a second micro-switch 335. The switch 335 is held open by the belt and when a notch 333 comes opposite to the roller—which is arranged to occur each time feed of the web is to start and when the finger 318 is out of notches 314 the roller drops into the notch 333 and the switch 335 closes. Closure of the switch energises the relay coil 321 which is, as already explained, self-holding. The relay therefore remains energised after the roller has left a notch and until the micro-switch 320 is opened.

The operation of the mechanism is, therefore, that feed of the web is initiated by the roller 334 on the second switch entering a notch in the belt 328 and the feed is stopped when the detent finger 318, released by the cam, enters a notch in the detent wheel and switch 320 opens. In order that the length of web which is fed at each operation may be varied, the position of the notch in the belt relative to the printing drum may be adjusted, for example, by means of a releasable clutch (not shown but, for example, of the dog or pin in sockets types) in the drive to the pin wheel. The position at which the feed is begun in each revolution of the printing drums and shaft 146 is therefore variable but the end of the feed is substantially constant in relation to the printing cylinders or drums. In other words the angular movement of shaft 72 and the length of web which is fed at each operation are variable but the stopping of the feed and movement of the shaft always occurs at substantially the same position of the printing cylinders, whatever the length that is fed.

In order to ensure that the mechanism shall not become locked by combined operation of the ratchet device 308, 310, and the cam and detent device 312, 316, 318, 313, the pawl 310 is carried on and fixed to a shaft 340 which also has fixed to it a lever 341 having a pin 342 slidable in a slot 343 in the end of a link 344 attached to the lever 316, adjacent the cam follower 317. The arrangement is such that as the finger 318 drops into a detent notch 314 the bottom of the slot 343 engages and pushes the pin 342 to rock the lever 341 and shaft 340 to disengage the pawl 310 from the ratchet 308. A compression spring 345 acts on the lever 316 to effect these operations.

A potentiometer or voltage adjuster 350 is provided in the supply lead to the relay 321 and solenoid 311 above described. The controlled voltage is also applied, through lead 351, to the coils of the brakes and clutches controlling the drive to the supply and re-wind reels 30 and 52. This enables the voltage applied to the coils of these members to be varied and hence the flux density in the coils to be varied. In use, when the rate of feed of the web is increased so is the applied voltage which causes an increase in the rate of reaction and effect of the various parts which helps to ensure that the correct tension is maintained in the web as the speed varies and also that the pawl 310 drops into the appropriate tooth of the epicyclic planet carrier.

Various modifications may be made in the above described example. For instance, it is not essential—although much to be preferred—that the operation of the switch 335 be effected by a flexible belt. For instance the belt 328 may be replaced by a rotatable disc with notches in its periphery or in the edge of a peripheral flange. The notches, whether on a belt or disc, may be replaced by projections, the switch in that case being normally open and closed by engagement of a projection

5 with the operating member 334. When a belt is used, it is not essential that it be of plastic, it may be of metal, nor is it essential that it be driven by a pin wheel. It may itself have driving projections on its inner surface engaging in notches in a driving pulley.

We claim:

1. A machine for printing continuous webs comprising a continuously driven printing couple, web-feeding rolls in continuous contact with the web to be printed, a roll driving shaft, and means for driving the said roll driving shaft intermittently, said means for driving the roll driving shaft intermittently comprising a drive shaft, a mechanical drive connection between said drive shaft and said driving shaft, said drive connection comprising a sun wheel in constant driven relation with said drive shaft, an internally gear-toothed annulus and means for transmitting rotation from said annulus to said roll driving shaft, a planet carrier rotatable about the axis of said sun wheel, a planet wheel rotatably supported by said carrier in meshing relation both with said sun wheel and with internally gear-toothed annulus, an electrically operated means for alternately arresting the rotation of said planet carrier and said internally gear-toothed annulus whereby alternately to cause said planet wheel to transmit rotation from said sun wheel to the internal gear-toothed annulus when the rotation of said planet carrier is arrested, and to cause said carrier and planet wheel to free wheel when the rotation of the internally gear-toothed annulus is arrested, and an adjustable endless programme member synchronously driven with said drive shaft controlling the operation of said electrically operated means.

2. A machine for printing continuous webs comprising a continuously driven printing couple, web-feeding rolls in continuous contact with the web to be printed, and means for driving the web-feeding rolls intermittently, said means for driving the web-feeding rolls intermittently comprising a drive shaft, a mechanical drive connection between said drive shaft and said rolls, said drive connection including an epicyclic gear mechanism having a sun wheel driven by said drive shaft, planet wheels carried by a rotatable carrier, an annulus meshing with the planet wheels geared to said driven shaft, and a free-wheel gear ring fast with the planet carrier, a pawl movable into and from engagement with the gear ring to arrest and free the planet carrier against and for rotation respectively so as to clutch drive at a reduced ratio to the annulus and hence to said driven shaft when the pawl is engaged with the ring and to de-clutch the drive so that the planet carrier free-wheels in the annulus when the pawl is disengaged, electrically operated means for moving said pawl, an adjustable endless programme member synchronously driven with said drive shaft for causing pawl and clutch operation, a mechanical detent for locking engagement with said rolls, and a connection between said drive shaft and said detent for engaging and disengaging the detent with the rolls at predetermined points in a printing cycle.

3. A machine as claimed in claim 2 wherein said electrically operated means for actuating said pawl comprise a solenoid, an electric circuit including a switch arranged to be closed by said programme member, and a holding circuit for maintaining said solenoid energised beyond re-opening of said switch.

4. A machine for printing continuous webs comprising a continuously driven printing couple, web-feeding rolls in continuous contact with the web to be printed, and means for driving the web-feeding rolls intermittently, said means for driving the web-feeding rolls intermittently comprising a drive shaft, a mechanical drive connection between said drive shaft and said rolls, a clutch operative to connect and disconnect said drive connection, a solenoid for actuating said clutch, an adjustable endless programme member synchronously driven with said drive shaft and having lateral discontinuities, a switch disposed

in the path of said discontinuities and adapted to be opened and closed thereby, an electric circuit including said switch and said solenoid, said circuit further including a relay and a holding circuit for maintaining said solenoid energised beyond re-opening of the switch, a mechanical detent for locking engagement with said rolls, a connection between said drive shaft and said detent for engaging and disengaging the detent with the rolls at predetermined points in the printing cycle, a second switch arranged adjacent the said connection between said drive shaft and detent and arranged, when closed, to complete said circuit including the solenoid, and when open to break said circuit.

5. A machine for printing continuous webs comprising a continuously driven printing couple, web-feeding rolls in continuous contact with the web to be printed, and means for driving the web-feeding rolls intermittently, said means for driving the web-feeding rolls intermittently comprising a drive shaft, an epicyclic gearing mechanism forming a drive connection between said drive shaft and said rolls, a pawl operative on said epicyclic gearing mechanism to connect and disconnect said drive connection, solenoid operated means for actuating said pawl, an adjustable endless programme member synchronously driven with said drive shaft and comprising a belt provided with lateral discontinuities, a drive hub for said belt, a switch located in the path of said discontinuities for actuation thereby, said switch being in a circuit including said solenoid, a mechanical detent for locking engagement with said rolls, and a connection between said drive shaft and said detent for engaging and disengaging the detent with a roll at predetermined points in a printing cycle.

6. A machine for printing continuous webs comprising a continuously driven printing couple, web-feeding rolls in continuous contact with the web to be printed, and means for driving the web-feeding rolls intermittently, said means for driving the web-feeding rolls intermittently comprising a drive shaft, a mechanical drive connection between said drive shaft and said rolls, a clutch operative to connect and disconnect said drive connection, an adjustable endless programme member synchronously driven with said drive shaft, a mechanical detent for locking engagement with said rolls, a connection between said drive shaft and said detent for engaging and disengaging the detent with the rolls at predetermined points in a printing cycle, an electromagnetic brake operable on said rolls, first switch means associated with said detent for operating said clutch, second switch means associated with said programme member and operable to actuate said clutch, said first switch means being connected also to said brake to apply the brake when said clutch is disengaged and release said brake when the detent is disengaged and the said first switch means are operated prior to operation of the second switch means and actuation of said clutch.

7. A machine for printing continuous webs comprising a continuously driven printing couple, web-feeding rolls in continuous contact with the web to be printed, and means for driving the web-feeding rolls intermittently, all of said web-feeding rolls being coupled to a common driving shaft, a drive shaft, a mechanical drive connection between said drive shaft and said driving shaft comprising an epicyclic gearing mechanism and a pawl operative to connect and disconnect drive through said epicyclic gearing mechanism, electrically operated means for actuating said pawl, an electromagnetic brake on said driving shaft, a notched wheel on said driving shaft, a cam on

10

said drive shaft, a detent, a lever pivoted for displacement by said cam and carrying said detent, switch means associated with said lever, and electrical circuits connecting said electrically operated means, said switch means, and further switch means associated with an adjustable programme member synchronously driven with said drive shaft for simultaneously disengaging the pawl and applying the brake as the detent engages a wheel notch and stops the wheel and rolls, and for releasing the brake as the detent disengages, and subsequently engaging the pawl.

8. A machine as claimed in claim 7 wherein a mechanical anti-lock link is provided connecting the lever carrying the detent and the pawl.
